United States Patent Office.

E. C. BARTON, OF BLOOMSBURG, PENNSYLVANIA.

Letters Patent No. 98,014, dated December 21, 1869.

IMPROVEMENT IN BORING-MACHINE.

The Schedule referred to in these Letters Patent and making part of the same.

To all whom it may concern:

Be it known that I, E. C. BARTON, of Bloomsburg, in the county of Columbia, and State of Pennsylvania, have invented a new and improved Boring-Machine; and I do hereby declare that the following is a full, clear, and exact description thereof, which will enable others skilled in the art to make and use the same, reference being had to the accompanying drawings, forming part of this specification.

This invention relates to improvements in wood-boring machines, whereby it is designed to provide a simple and efficient arrangement of frame and operating-devices.

Figure 1 represents a side elevation of my improved machine, partly broken out, and

Figure 2 represents a transverse section of the same.

Similar letters of reference indicate corresponding parts.

A represents a box-shaped frame, supported on legs B at each end.

The end walls of this frame serve as bearings for a worm-driving shaft, C, preferably so arranged that the top of the said worm-shaft is about the same height as the side walls of the frame, whereon are supported transversely, in suitable bearings D, one or more boring-mandrels E, having pinions gearing with the worm-shaft.

The latter is driven by a belt, F, from the main driving-shaft G.

The bearings D for the mandrels have yoked extensions D', extending to near the bottom of the frame A, which is slotted longitudinally, through which slots

holding-screws H screw into the said yokes, to clamp the bearings down tightly upon the top of the frame A, or they may be raised up by the screws, to carry the pinions of the boring-mandrels out of gear with the worm-shaft C. The said screws have collars above and below the bottom of the frame for holding them, so as to control the yokes. These yokes and the bearings may be adjusted along the frame.

The work-holding table K is supported on brackets L, on one side of the frame A, capable of sliding up and down thereon, and under these brackets is placed a slide, M, having inclined planes N, and an adjusting-screw, O, by which it may be moved back and forth under the brackets.

The movement of the said slide M one way, forces the brackets up, and the other way, lets them down. In this way the pieces to be bored may be gauged for any required distance from the side lying in the table.

The brackets, or the side of the frame A may be provided with scales, to indicate the distance of the table from the boring-tools.

Having thus described my invention,

What I claim as new, and desire to secure by Letters Patent, is—

The mandrel E and its pinion, the yoke D D', and collared screw-bolt H, in combination with the worm C and frame A, when constructed, arranged, and operating substantially as herein shown and described.

E. C. BARTON.
